UNITED STATES PATENT OFFICE.

CHARLES FRANCIS JENKINS, OF WASHINGTON, DISTRICT OF COLUMBIA, ASSIGNOR TO THE GRAPHOSCOPE COMPANY, OF WASHINGTON, DISTRICT OF COLUMBIA, A CORPORATION OF DELAWARE.

MOTION-PICTURE APPARATUS.

1,229,275.

Specification of Letters Patent. Patented June 12, 1917.

Application filed April 6, 1916. Serial No. 89,323.

To all whom it may concern:

Be it known that I, CHARLES FRANCIS JENKINS, a citizen of the United States, residing at Washington, in the District of Columbia, have invented certain new and useful Improvements in Motion-Picture Apparatus, of which the following is a specification, reference being had therein to the accompanying drawing.

- 10 The object of this invention is to provide for the use of the same special motion picture film in either a machine which uses standard film or in one in which standard film cannot be used.
- 15 It is well known that in general standard, highly inflammable motion picture film cannot now be used outside of a practically fireproof cabinet, and that the same restrictions apply to the use of any machine adapted to feed such standard film. Slow-burning film may be used in a special machine incapable of feeding standard film, and without infringing upon any insurance or municipal rules or regulations, and, for example, such machine or film may be used in any room or may be removed from room to room in any school or dwelling as often as may be desired. Heretofore, so far as I am aware, this plan has involved providing a second film if it were desired to show the same reel or subject matter by using a standard machine, and as long films are expensive and also heavy and so more or less inconvenient to carry about in large numbers, the saving of one or two reels is important. This invention involves the use of film so perforated that it may be used in either a standard machine or in a special machine in which standard film cannot be used.

In the accompanying drawings,

Figure 1 shows a standard sprocket drum and an axially aligned special drum having at regular intervals certain teeth of the standard drum replaced by special teeth which cannot enter the perforations of standard film.

Fig. 2 is an end view of the special drum of Fig. 1.

50 Fig. 3 shows parallel slightly separated portions of a standard film and a special film adapted for use with the drums of Figs. 1 and 2.

In these figures, A represents a standard sprocket drum and B a similar drum in which sets of standard teeth, shown as having two teeth in a set, alternate with special teeth C which in this instance occupy precisely the same space as two consecutive standard teeth D plus the space between the two, so that the forward face of this long tooth lies in the plane which would be occupied by the forward face of the foremost regular tooth which is replaced. All the teeth are of substantially the same thickness, measured parallel to the drum axis.

Obviously the film E, Fig. 3, which is standard film, cannot be used on the special drum, since it has no long perforations to receive the long teeth C, but the special film F which has such long perforations may be so used and evidently may also be used on a standard sprocket drum, two consecutive teeth of which exactly fill the long perforation. One standard tooth and its forward face are lost, but that is not material since several teeth are at all times engaged.

The parallel lines $x-x$, $y-y$, Figs. 1 and 3, show to the eye that the long tooth occupies exactly the same space as two consecutive standard teeth. It is not indispensable that there should be two teeth in each set intervening and separating consecutive long teeth or those occupying unusual angular space, nor is it necessary to limit the length of the long teeth, although the forward face of each long tooth should lie exactly in the plane of the forward face of the displaced standard tooth.

What I claim is:

1. A film feeding sprocket drum having at regular intervals special teeth in circumferential extent exceeding the extent of the perforations of standard film longitudinally thereof, but each having its forward face precisely in the plane which would be occupied by the forward face of a tooth were all the teeth those of a standard sprocket drum.

2. A film feeding sprocket drum having teeth of unequal circumferential extent, the forward faces of all being in position to engage the forward sides of the corresponding perforations of standard film.

3. A film feeding sprocket drum having

sets of teeth each in form and location like the corresponding teeth of standard film, the sets alternating with teeth of greater circumferential extent each having its forward face in the plane which would be occupied by the forward face of a standard tooth in a corresponding standard drum.

4. A film having sets of standard perforations, the sets alternating with perforations each equal in linear extent to the space 10 occupied by a plurality of consecutive perforations of standard film.

CHARLES FRANCIS JENKINS.
